UNITED STATES PATENT OFFICE.

JAMES M. MUNYON, OF PHILADELPHIA, PENNSYLVANIA.

DESIGN FOR AN INHALER.

SPECIFICATION forming part of Design No. 30,312, dated **March 7, 1899.**

Application filed February 9, 1899. Serial No. 705,118. Term of patent 14 years.

To all whom it may concern:

Be it known that I, JAMES M. MUNYON, a citizen of the United States, residing in the city and county of Philadelphia, State of Pennsylvania, have invented and produced a new and original Design for an Inhaler, of which the following is a specification, reference being had to the accompanying drawings, forming part thereof.

5 The leading feature of my design for an inhaler is a body consisting of side tubes and a web between the same.

Figure 1 represents a side elevation of an inhaler embodying my design. Fig. 2 represents a vertical section view thereof. Fig. 3 represents a horizontal section thereof on line *x x*, Fig. 1.

In the drawings, A designates the body of the inhaler, the same consisting of the side tubes B and C, and the neck or web D between the same.

E designates a mouthpiece on one of the tubes, and F designates a cap on the other tube.

Having thus described my invention, what I claim as new, and desire to secure by Letters Patent, is—

The design for an inhaler substantially as shown and described.

JAMES M. MUNYON.
